ELECTRIC CIRCUIT BREAKER

Hans Thommen, Ennetbaden, Switzerland, assignor to Aktiengesellschaft Brown Boveri & Cie., Baden, Switzerland, a joint-stock company of Switzerland

Application July 6, 1932, Serial No. 621,039
In Germany July 6, 1931

13 Claims. (Cl. 200—150)

This invention relates to improvements in electric circuit breakers and more particularly to the type of circuit breaker in which an arc, formed upon separation of the contacts to interrupt the circuit, is quenched by the interposition of an insulating fluid between the contacts.

When an electric power circuit is interrupted by a circuit breaker with the contacts thereof immersed in an insulating fluid such as oil, the fluid is partially vaporized by the arc formed, thus producing pressure by which the fluid is forced away from the vicinity of the arc. When the contacts are separated in a fluid retained within a closed chamber, the pressure forces the fluid from the chamber through the openings provided therefor or for movement of the movable contact therethrough. The flow of fluid through such openings cools the arc and deionizes the gas formed thereby and conducting the same and causes quenching of the arc thus interrupting the circuit. In the usual construction of such circuit breakers the oil blast takes place in only one direction and diminishes with decrease in the gas production. The interrupting action of the oil blast can be materially improved if the chamber is so constructed as to produce an oil flow in both directions from the center of the arc about the points of attachment of the arc on the contacts and if means are provided by which the oil flow is continued even after the production of gas has ceased.

It is, therefore, among the objects of the present invention to provide an electric circuit breaker of the interposed insulating fluid arc quenching type in which the arc produces gases which cause the formation of fluid blasts about the arc.

Another object of the invention is to provide an electric circuit breaker of the interposed insulating fluid arc quenching type in which the circuit is interrupted in a chamber so constructed that fluid blasts are produced directed toward the points of attachment of the arc on the contacts of the circuit breaker.

Another object of the invention is to provide an electric circuit breaker of the interposed insulating fluid arc quenching type in which the circuit is interrupted in a chamber so constructed that fluid blasts are produced in both directions from the center of the arc about the contacts of the circuit breaker.

Another object of the invention is to provide an electric circuit breaker of the interposed insulating fluid arc quenching type in which the circuit is interrupted in a chamber so constructed that the fluid blasts, produced upon separation of

the contacts of the circuit breaker to interrupt the circuit, are continued after the gas producing action of the arc has ceased.

Objects and advantages other than those above set forth will be apparent from the following description when read in connection with the accompanying drawing in which:

Fig. 1 is a partial vertical sectional view of a portion of an electric circuit breaker of the interposed insulating fluid arc quenching type embodying the present invention;

Fig. 2 is a vertical sectional view of a pressure pot similar to that shown in Fig. 1, but having an additional partition member;

Fig. 3 is a vertical sectional view of a preferred form of a pressure pot embodying the invention; and

Fig. 4 is a vertical sectional view of a pressure pot which is a modification of Fig. 3, and embodies the present invention.

Referring more particularly to the drawing by characters of reference, the reference numeral 6 designates a portion of a chamber or tank provided with a top or cover 7 and designed to enclose the operating portions of a circuit breaker structure within a body of oil such as indicated at 8. Hollow insulating bushings 11 extend through the top plate 7 and support substantially closed chambers 12 within each of which is arranged a fixed contact 13 which contacts are each connected with the electric circuit (not shown) exterior of the tank by a conductor 14 connected with a conductor 15 extending through the bushing 11. An aperture 16 is provided in the top of the chamber 12 to permit a contact 17 to be moved into and out of engagement with the fixed contact 13. A second aperture 18 is provided in the exterior wall of the chamber 12 below the oil level within the tank 6 for a purpose which will appear hereinafter.

A second chamber 21 is arranged coaxially within chamber 12 and is secured to or integral with the top of the chamber 12 as shown, thereby forming with chamber 12 a substantially enclosed space above the oil level within the tank 6. The chamber 21 is provided with a partition 22 which has an aperture 23 therethrough in alignment with the aperture 16 through the top of the chamber 12 and with an aperture 24 through the bottom of the chamber 21 above the fixed contact 13. The movable contact 17 may thus be moved into and out of engagement with fixed contact 13 through the aligned apertures through the chambers 12 and 21 by means of a cross bar 26 connected with the contact and connected with

an operating rod 27 which is arranged to be moved by any of the usual operating means which are, therefore, not shown. It will be understood, of course, that the portion of the structure shown in elevation on the right hand side of Fig. 1 corresponds to the portion of the structure described immediately above and shown on the left hand side of Fig. 1.

When the electric circuit (not shown), in which the contacts 13 and 17 are connected, is interrupted; the contact 17 is moved out of engagement with contact 13. As soon as the contacts are separated from each other the arc formed acts on the oil and produces partial vaporization thereof which forces the unvaporized oil in chamber 12 upwardly, thus securing a compression of the gases in the chamber 12 above the oil level. Further movement of contact 17 through apertures 24 and 23 in succession draws the arc out and causes the oil in chamber 21 to be partially vaporized. Such vaporization produces a high pressure which causes an oil blast to flow through apertures 24 and 23 in sequence in opposite directions due to expansion of the gases in the chamber 21. The oil blast through aperture 24 surrounds and moves over the fixed contact 13 and the oil blast flowing through aperture 23 moves over contact 17. As soon as the gas produced in chamber 21 diminishes, thus decreasing the pressure on the oil in chamber 12, the previously compressed gases in the upper portion of chamber 12 force oil to surround the fixed contact 13 and to flow through aperture 24 into chamber 21 in a direction opposite to that taken by the oil blast from such chamber when the movable contact 17 was drawn thereinto. The excess and incondensable gases collect in the upper portion of chamber 12 and escape therefrom through aperture 18 and sufficient oil then enters the chambers 12 and 21 through such aperture to maintain the level therein substantially the same as that in tank 6.

The contact enclosing chambers shown in the embodiment in Fig. 2 are substantially similar to the embodiment illustrated in Fig. 1 excepting for the provision of a partition 28 arranged across chamber 21 and provided with an aperture 29 in alignment with apertures 23 and 24 thus dividing chamber 21 into two portions. The arc quenching and circuit interrupting action which takes place in the present embodiment is also similar to that described as taking place in the embodiment shown in Fig. 1 with the exception that an oil blast is forced through apertures 24 and 29 in opposite directions as long as the end of the movable contact 17 is between the bottom of the chamber 21 and the partition 28 and that the direction of the oil blast through aperture 29 is reversed as soon as contact 17 moves between partitions 28 and 22 thus producing oil blasts in opposite directions through apertures 23 and 29. The reversal of the direction of oil flow through the apertures through the walls of the chamber 21 causes an intensive cooling and deionization of those portions of the gases providing a conductive path for the arc immediately adjacent such apertures and materially facilitates the interruption of the circuit by expediting the quenching of the arc.

Fig. 3 illustrates a modified embodiment of the invention which is similar to that shown in Fig. 2 excepting that the chamber 21 is divided into several substantially closed portions by partitions 31 and 32 arranged between the upper wall 22 of the chamber 21 and the bottom of the chamber

21. Each of the partitions 31 and 32 is provided with an aperture therethrough designated by reference numerals 33 and 34 respectively. Apertures 36 and 37 are provided through the side wall of chamber 21 between the partitions 31 and 32. When contact 17 is moved out of engagement with fixed contact 13 the gases formed by the arc within chamber 12 force the oil therein upwardly to compress the gases in the upper portion of such chamber. Further movement of movable contact 17 and extension of the arc into chamber 21 between partition 32 and the bottom thereof produces an oil blast through apertures 34 and 24 in opposite directions. Movement of movable contact 17 between partitions 31 and 22 likewise causes an oil blast through apertures 33 and 23 in opposite directions. The oil blasts through apertures 34 and 33 meet in the space between partitions 31 and 32 and flow radially through apertures 36 and 37 into chamber 12. Decrease of the gases produced by the action of the arc on the oil in the several portions of the chamber 21 by flow of the oil through the apertures therein permits the gases compressed at the beginning of the circuit interrupting action in the upper portion of the chamber 12 to expand and to force oil through apertures 24, 34, 33 and 23 in the reverse direction from that described immediately above, thus materially increasing the effectiveness of the arc quenching action of the oil.

Under some circumstances, it may be desirable to omit reversal of the direction of the oil flow through the apertures as described above with reference to Figs. 1, 2 and 3. In such case chamber 12 shown in Figs. 1, 2 and 3 is merely omitted as illustrated in Fig. 4 and the apertures from chamber 21 are arranged to discharge directly into tank 6. If an interrupting action has taken place which causes expulsion of the oil from the several closed portions of chamber 21 oil will flow back into such closed portions through the apertures therethrough from the tank, thus causing a complete filling of all of the portions of chamber 21 after each circuit interrupting action. The oil blasts then flow through the several apertures from the spaces in which the gases are produced at relatively high pressure directly into the oil retained within the tank 6 under the low pressure therein. When the chamber 12 is omitted the fixed contact 13 is supported in alignment with the apertures through the top, the partitions and the bottom of chamber 21 by suitable means such as the supports 41 secured to the chamber 21 by means such as the bolts 42.

Although but a few embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

1. In an electric circuit breaker, a tank containing arc extinguishing liquid, an insulating bushing extending into said tank, a pressure pot secured to said insulating bushing and immersed in said liquid so as to form an air space above the oil in said pot, a fixed contact arranged within said pot, said pot having an opening therein in alignment with said fixed contact, a tubular insulating member within said pressure pot and secured thereto adjacent said opening, means including a movable contact rod extending through

said opening and said member into engagement with said fixed contact whereby upon disengagement of said contacts the arc is first formed within in said pot but externally of said member, and a plurality of spaced partitions secured within said pressure pot, said partitions having holes therethrough in alinement with the opening in said pressure pot.

2. In an electric circuit breaker, a tank containing arc extinguishing liquid, an insulating member extending into said tank, a pressure pot secured to said insulating member and partially immersed in said fluid, a smaller pressure pot within said pressure pot forming a pressure chamber between said pots, a fixed contact mounted within said pressure pot but externally of said smaller pressure pot, said pressure pot having an opening therethrough in alinement with said fixed contact, a contact rod movable through said opening into engagement with said fixed contact, and means secured within said smaller pressure pot defining a series of chambers interconnected by aligned openings for the passage of said contact rod, and for the discharge of arc extinguishing liquid.

3. In an electric circuit breaker, a tank containing arc extinguishing liquid, an insulating member extending into said tank, a pressure pot secured to said insulating member and partially immersed in said fluid, a fixed contact mounted within said pressure pot, said pressure pot having an opening therethrough in alinement with said fixed contact, a contact rod movable through said opening into engagement with said fixed contact, an insulating structure secured to the interior of said pressure pot adjacent said opening, said structure defining a series of closed chambers of considerably smaller lateral dimensions than said pressure pot, said chambers having aligned openings therethrough in communication with said opening in said pressure pot for the discharge of arc extinguishing liquid the lowermost of said aligned openings being directly above said fixed contact, and means for equalizing the level of the oil in the said tank and said pressure pot so as to provide an air space above the oil level between said pressure pot and said structure.

4. In an electric circuit breaker, a tank containing arc extinguishing liquid, an insulating member extending into said tank, a pressure pot secured to said insulating member and immersed in said fluid, a fixed contact mounted within said pressure pot, said pressure pot having an opening therethrough in alinement with said fixed contact, a contact rod movable through said opening into engagement with said fixed contact, and a second pressure pot in communication with said first mentioned pressure pot through said opening, said second pressure pot having a plurality of partitions therein having holes therethrough in alinement with said opening and means whereby upon disconnection of said contact said arc extinguishing liquid is forced through said opening first in one direction and then in the other direction.

5. In an electric circuit breaker, a tank containing arc extinguishing liquid, an insulating member extending into said tank, a pressure pot secured to said insulating member and immersed in said fluid, a fixed contact mounted within said pressure pot, said pressure pot having an opening therethrough in alinement with said fixed contact, a contact rod movable through said opening into engagement with said fixed contact, and an auxiliary pressure pot secured to said

first mentioned pressure pot so as to be in communication with said opening, said second pressure pot having a plurality of partitions therein forming a series of chambers interconnected by openings in said partitions in alinement with the opening in said first mentioned pressure pot, said auxiliary pressure pot having a plurality of additional openings therein for the lateral discharge of arc extinguishing liquid.

6. In an electric circuit breaker, a tank containing arc extinguishing liquid, an insulating member extending into said tank, a pressure pot secured to said insulating member and immersed in said fluid, a fixed contact mounted within said pressure pot, said pressure pot having an opening therethrough in alinement with said fixed contact, a contact rod movable through said opening into engagement with said fixed contact, and an auxiliary pressure pot secured within said first mentioned pressure pot so as to surround said opening, said second pressure pot having a plurality of partitions therein forming a series of chambers interconnected by openings in said partitions in alinement with said opening in said pressure pot, said second pressure pot also having a plurality of additional openings therein constituting discharge passageways between said pressure pots.

7. In an electric circuit breaker, a tank containing an arc extinguishing liquid, an insulating member extending into said tank, a pressure pot secured to said insulating member and immersed in said liquid, said pressure pot having a plurality of partitions therein with vertically aligned holes therethrough defining a series of inter-communicating chambers, one of said chambers having an additional opening for the lateral discharge of arc extinguishing liquid into said tank, and means for drawing an arc through said vertically aligned holes.

8. In an electric circuit breaker, a tank containing an arc extinguishing liquid, an insulating member extending into said tank, a pressure pot secured to said insulating member and immersed in said liquid, said pressure pot having a plurality of partitions therein with vertically aligned holes therethrough defining a series of inter-communicating chambers, said pressure pot having a transverse discharge passageway opening into said tank from one of said chambers which is immediately adjacent and between two of said chambers, and relatively movable contacts for drawing an arc through said vertically aligned holes.

9. In an electric circuit breaker, a tank containing an arc extinguishing liquid, an insulating member extending into said tank, a pressure pot secured to said insulating member and immersed in said liquid, said pressure pot having a plurality of partitions therein with vertically aligned holes therethrough defining a series of inter-communicating chambers, said pressure pot having a transverse discharge passageway opening into said tank from one of said chambers which is immediately adjacent and between two of said chambers, a fixed contact carried by said pressure pot in alinement with said aligned holes, said partitions being so spaced that when said movable contact is withdrawn from said fixed contact it first passes through a plurality of relatively small chambers and then through a larger chamber.

10. In an electric circuit breaker, a closed chamber to retain a quantity of insulating fluid, an insulating bushing extending into said chamber, a substantially closed chamber supported by said

bushing and extending into the fluid, the second said chamber being divided into an inner and an outer portion forming a gas compressing chamber above the level of the fluid in the first said 5 chamber, a fixed contact arranged within the second said chamber, and a contact extending into the second said chamber and movable into and out of engagement with said fixed contact.

11. In an electric circuit breaker, a closed 10 chamber to retain a quantity of insulating fluid, an insulating bushing extending into said chamber, a substantially closed chamber supported by said bushing and extending into the fluid, the second of said chambers being divided into an 15 outer and an inner portion, the outer portion of said chamber having an aperture below the level of the fluid in the first said chamber, a fixed contact arranged within the second said chamber, and a contact extending into the second said 20 chamber and movable into and out of engagement with said fixed contact.

12. In an electric circuit breaker, a closed 25 chamber to retain a quantity of insulating fluid, an insulating bushing extending into said chamber, a substantially closed chamber supported by said bushing and extending into the fluid, the second of said chambers being divided into an outer and an inner portion, the inner portion of

said chamber being divided into a plurality of portions having apertures for discharging into the outer portion thereof, a fixed contact arranged within the second said chamber, and a contact extending into the second said chamber and movable into and out of engagement with said fixed contact.

13. In an electric circuit breaker, a closed chamber to retain a quantity of insulating fluid, an insulating bushing extending into said chamber, a substantially closed chamber supported by said bushing and extending into the fluid, the second said chamber being divided into an inner and an outer portion having aligned apertures in the walls thereof, the outer portion of said chamber having an aperture below the level of the fluid in the first said chamber and the inner portion of said chamber being divided into a plurality of closed portions having apertures for discharging only into the outer portion thereof, a fixed contact arranged within the second said chamber, and a contact extending into the second said chamber and movable into and out of engagement with said fixed contact, said movable contact substantially closing the apertures in the inner portions of the second said chamber when engaging said fixed contact.

HANS THOMMEN.
